UNITED STATES PATENT OFFICE.

JOHN DAMM, OF BROCKTON, PENNSYLVANIA.

CONDENSER.

1,402,575.

Specification of Letters Patent. Patented Jan. 3, 1922.

Application filed March 2, 1920. Serial No. 362,719.

To all whom it may concern:

Be it known that JOHN DAMM, a citizen of the United States of America, residing at Brockton, in the county of Schuylkill and State of Pennsylvania, has invented new and useful Improvements in Condensers, of which the following is a specification.

The object of the invention is to provide a simple and efficient means for condensing the exhaust steam used in the operation of mine pump engines, utilizing a portion of the water supplied by the pump for facilitating the condensation of the steam and with this object in view the invention consists in a construction and combination of parts of which a preferred embodiment is shown in the drawing, wherein:

Figure 1 is a general view of the apparatus.

20 Figure 2 is a sectional view of the dome and condenser casing in which the same is housed.

Figure 3 is a sectional view of the mud hopper.

25 Figure 4 is a horizontal sectional view on the plane indicated by the line 4—4 of Figure 2.

Figure 5 is a vertical sectional view on the plane indicated by the line 5—5 of 30 Figure 2.

The exhaust pipe 10 from the engine leads to the condenser casing 11 and discharges into a dome 12 housed within the casing and provided preferably in the wall opposite to 35 the entrance of the exhaust pipe, with discharge perforations 13 formed in a wall which is exposed to the discharge from a spray nozzle 14 supplied by a branch pipe 15 leading from a discharge pipe 16 which 40 terminates in a discharge nozzle 17 located in the lower and preferably tapered or funnel-shaped portion 18 of the casing in alignment with an outlet passage 19.

The spray pipe 15 is preferably provided 45 with a valve 20 by which it may be controlled, and a similar valve 21 is preferably located in the discharge pipe 16 for a similar purpose, while the discharge nozzle 17 consists of an inner glass or non-corrosive lining 22 disposed in a protecting shell 23 of brass which constitutes a housing.

The water to supply the spray nozzle and the discharge nozzle is conveyed to the mud hopper or mud drum 24 by the pump discharge pipe 25 having a suitable controlling valve 26, said hopper having a blowout pipe 27 fitted with a controlling valve 28, and by the closing of the latter and the adjustment of the valve 26, the desired pressure may be secured in the mud hopper or drum under 55 the further control of the valves 20 and 21 arranged as above described respectively in the spray pipe 15 and discharge pipe 16 to control the rapidity of discharge from the spray nozzle 14 and discharge nozzle 17. 60

As the steam from the engine exhaust escapes from the dome 12 it is exposed to the action of the water spray from the nozzle 14 and thence passes downward into the reduced or funnel-shaped portion of the condenser casing where it is encountered by the discharge from the nozzle 17 to complete the condensation, said discharge nozzle 17 by reason of being directed toward the outlet 75 19 serving to create a tension or suction due to the rarification of the air in the condenser casing to insure the effective induction of the exhaust steam to the dome.

A mud screen 29 is located within the mud hopper or drum in communication with the water discharge pipe 16 to prevent dirt or foreign matter from the pump from entering the condenser, and obviously from time to time the blow-off valve 28 may be opened to remove accumulations from the 80 interior of the mud hopper.

What is claimed is:

1. A condenser for mine pump engines and the like having a condenser casing provided with an enclosed steam dome for the reception of the exhaust steam, said steam dome having discharge perforations in an exposed wall thereof, a pump fed spray nozzle for discharging water in a path intersecting that of discharge from said steam dome, and a suction-inducing discharge nozzle located within the condenser casing and directed toward the outlet thereof. 90

2. A condenser for mine pump engines and the like having a condenser casing provided with a depending tapered or reduced portion terminating in an outlet, a steam

dome housed within the casing and in communication with the engine exhaust, said dome being provided with discharge perforations in communication with the interior 5 of the casing, a pump fed spray nozzle for discharging a spray in a path intersecting the discharge from said dome, and a pump

fed discharge nozzle located in the reduced portion of the casing and directed toward the outlet thereof.

In testimony whereof he affixes his signature.

JOHN DAMM.
